UNITED STATES PATENT OFFICE.

CHARLES KITSCHELT, OF NEW YORK, N. Y., ASSIGNOR TO NICHOLAS MULLER'S SONS & CO., OF SAME PLACE.

DESIGN FOR CLOCK-STAND.

SPECIFICATION forming part of Design No. 11,811, dated June 8, 1880.

Application filed May 8, 1880. Term of patent 7 years.

To all whom it may concern:

Be it known that I, CHARLES KITSCHELT, of the city, county, and State of New York, have invented a new and original Design for Clock-Stands, of which the following is a full, clear, and exact description.

The nature of my design is fully represented in the accompanying drawing, to which reference is made.

This invention relates to an improved design for a clock-stand; and it consists of an ornamental base with a central anchor and coiled rope at its front and dolphin-shaped legs at the sides, and of two helmsmen, shown in the act of operating a steering-wheel, within which the clock is arranged.

In the drawings, A represents the supporting-base of my improved clock-stand, which is supported on side legs, *a*, in the shape of dolphins, and provided with a central front ornament consisting of an anchor and a coil of rope. On a center stand, B, of the base is supported a steering-wheel, C, at each side of which a helmsman, D, is shown in the act

of taking hold of the spokes of the wheel C, 25 as shown in the accompanying drawing. Within the steering-wheel a clock or other article, E, is arranged.

Having thus described my invention, I claim as new and desire to secure by Letters Patent—

1. The design for a clock-stand, consisting of a supporting-base, A, a central stand, B, a steering-wheel, C, and a helmsman, D, at each side thereof, as shown and described. 35

2. The design for the base of a clock-stand, consisting of an elongated base having dolphin-shaped side legs and a central front ornament formed of an anchor and coil of rope, as shown and described. 40

In testimony that I claim the foregoing as my invention I have signed it this 20th day of April, 1880.

CHARLES KITSCHELT.
